SIGNAL TRANSMISSION SYSTEM

Edwin W. Kenefake and Frank M. Rives, Schenectady, N. Y., assignors to General Electric Company, a corporation of New York

Application September 17, 1942, Serial No. 458,618

3 Claims. (Cl. 179—2.5)

This invention relates to signal transmission systems, and more particularly to such systems in which signals are transmitted by means of a carrier wave.

In systems arranged to transmit signal modulated carrier waves over a power transmission line, the carrier wave may be influenced undesirably during its transmission along the power line. Static, and similar electrical disturbances, usually encountered in radio reception, having components of the same frequency as the carrier wave, are negligibly small on a power transmission line. It has been found, however, that, although the carrier wave is not intermixed in its transmission along the power line with such static and other electrical disturbances, it is attenuated in varying amounts by fluctuating corona losses and the like along the power transmission line. Such variable attenuation changes in large amounts at audible frequency, and introduces an undesirable modulation of the carrier wave.

It has been considered necessary to overcome such undesirable modulation of the carrier wave transmitted along a power transmission line by utilizing a carrier wave transmitter of sufficient power to minimize the effect of this undesirable modulation. This has been only a partial solution, since the modulation produced by such corona losses and the like act to modulate a strong carrier wave nearly as much as a weaker one.

It is an object of our invention to provide a new and improved signal modulated carrier wave transmission system whereby such carrier waves may be transmitted over power transmission lines with minimum interference.

Carrier wave systems are frequently arranged for signal transmission back and forth between two separate stations on the same frequency. Such signal transmission requires that the transmitter at a station be turned off before the receiver is operative to receive a signal from the other station. It is desirable to provide automatic means to carry out such switching of the transmitters and receivers at the stations, and such automatic switching should be so rapid in response to the presence or absence of signals as to avoid any apparent loss of the beginning of a message. Extremely rapid switching introduces transients in the carrier wave transmission system which are similar to the variable attenuations previously described.

It is a further object of our invention to provide a new and improved signal modulated carrier wave transmission system in which such extremely rapid switching may be used and in which

the resulting transients introduced in the carrier wave transmission system produce minimum effect in the signal channel.

It is also an object of our invention to provide a new and improved signal transmission system in which the signal source is automatically connected to the signal transmission channel in response to the appearance of signals in a minimum time and with minimum loss of signals and minimum effect upon the signals.

The features of our invention which we believe to be novel are set forth with particularity in the appended claims. The invention itself, both as to its organization and manner of operation, together with further objects and advantages thereof may best be understood by reference to the following description taken in connection with the accompanying drawings in which Figs. 1a and 1b are two parts of a schematic illustration of a signal transmission system embodying our invention.

In Fig. 1b a power transmission line is illustrated at 10 as extending between two separate stations, one of which includes a carrier wave transmitter 11 and a carrier wave receiver 12 connected with a hand set 13, which includes a microphone and a sound reproducer. A similar transmitter and receiver, illustrated in detail, are connected with the power line 10 and with a hand set 14.

30 The transmitter thus illustrated in detail comprises a carrier wave generator having an oscillating discharge device 20, and means including a pair of discharge devices 21 and 22 effective to modulate the frequency of oscillations generated by the device 20 in accordance with signals from the hand set 14. The carrier wave generated by the device 20 is amplified through a power amplifier device 23 and impressed on the power line 10.

40 The receiver includes electron discharge frequency converter 24, which converts the frequency of received frequency modulated carrier waves to a fixed frequency for amplification in an electron discharge amplifier device 25. The amplified carrier wave from the discharge device 25 is further amplified and its intensity limited to a substantially constant value in another electron discharge amplifier device 26. The amplified and limited frequency modulated carrier wave from the device 26 is demodulated by a pair of rectifier devices 27 and 28, which reproduce signal voltages from the frequency modulated carrier waves, which signal voltages are amplified through two amplifier discharge devices 29 and 30 and reproduced as sound by the hand set 14.

Control means is associated with each transmitter and receiver to render the receiver inoperative and start the transmitter whenever signals appear from the hand set 14. This control means is also effective to prevent operation of the transmitter and connect the receiver to reproduce signals in the hand set 14, in response to the reception of carrier waves from the power line 10. This control means is similar to that described and claimed in the copending application, S. N. 450,499, filed July 11, 1942, by Edwin W. Kenefake for High frequency communication systems, the present control means being arranged and adjusted in a somewhat different and improved manner in accordance with the present invention.

This control means includes a vapor discharge device 40 which is responsive to signals from the hand set 14 to initiate and maintain generation of carrier wave oscillations by the device 20. The device 40 is also effective in conjunction with the electron discharge device 41 and the rectifier device 42 to prevent operation of the carrier wave generator 20 when the frequency converter device 24 and amplifier 25 receive carrier waves from the power line 10. Further, the vapor discharge device 40 operating through a relay 43 and an electron discharge device 44 is effective to block operation of the frequency converter device 24 in response to signals from the hand set 14. An electron discharge device 45 in the receiver is effective to make the amplifier devices 29 and 30 operative to transmit signals from the rectifier devices 27 and 28 to the hand set 14 when a carrier wave is received from the power line 10.

The oscillator including the electron discharge device 20 is a usual type which is made operative when the conductor 50 is connected to ground. The cathode 51 of device 20 is grounded for high frequency current through a suitable condenser 52, and is connected through a resistance 53 to the conductor 50, the resistance 53 being of suitable value to provide a proper operating bias between the control electrode 54 of the device 20 and the cathode 51 when the discharge current of the device 20 flows through the resistance 53. The resistance 53 and condenser 52 are made sufficiently small that, when the conductor 50 is grounded, the cathode 51 rapidly attains a constant positive potential with respect to ground equal to the drop in potential through resistance 53, the time before the cathode reaches this constant potential after the conductor 50 is grounded being in the order of 1 millisecond or less.

The operating circuit of the oscillator includes a tuned circuit having an inductance 55 and a condenser 56, connected in parallel. The control electrode 54 is coupled to one end of this tuned circuit through a suitable coupling condenser 57, and the anode 58 of the device 20 is connected directly to the other end of the tuned circuit. An intermediate tap of the inductance 55 is connected to the positive terminal of a source 59 of operating potential, the negative terminal of which is grounded. By such connection, operating current from the source 59 is supplied through the inductance 55 to the anode 58 of the device 20 such current flowing through the cathode 51, and resistance 53 to ground when the device 20 is operating. A suitable grid resistance 60 is connected between the control electrode 54 and the cathode 51 to allow current to flow between the control electrode 54 and

cathode 51 during oscillation of the device 20. The screen electrode 61 of the device 20 is connected to an intermediate tap on the source 59, positive in potential with respect to ground, so that connection of the conductor 50 to ground and its disconnection therefrom are effective to make the device 20 and tuned circuit 55, 56 go smoothly into and out of oscillation as the potential of the cathode 51 becomes more or less positive with respect to ground.

Oscillations appearing on the anode 58 of the device 20 are amplified through device 23, whose anode 70 is connected through an inductance 71 to the positive terminal of source 59. The anode 70 is coupled through a coupling condenser 72 to one terminal of a tuned circuit 73, whose other terminal is grounded. The control electrode 74 of the device 23 is coupled through a serially connected condenser 75 and resistance 76 to the anode 58 of the device 20. The cathode 77 of device 23 is connected to ground through a suitable biasing resistance 78, bypassed by a condenser 79. A suitable grid resistance 80 is connected between the control electrode 74 of device 23 and ground, to provide for the maintenance of suitable bias potential between the control electrode 74 and cathode 77.

Oscillations produced on the anode 58 of the oscillator device 20 are amplified through the device 23, and appear across the tuned circuit 73, of which an intermediate tap 90 is connected through an inductance 91 and a coupling and insulating condenser 92 to the power line 10. The inductance 91 is of such value as to resonate with the coupling and insulating condenser 92 at the frequency of oscillations produced by the transmitter.

The frequency of oscillations produced by the oscillator device 20 is varied in accordance with signals from the hand set 14 by the two discharge devices 21 and 22, so arranged as to simulate reactances. The device 21 is so arranged as to simulate a capacity, and the device 22 is so arranged as to simulate an inductance. Signal potentials from the hand set 14 are applied to the respective control electrodes 93 and 94 of the devices 21 and 22 in push-pull, or balanced, relation, so that an increase of the apparent capacity of device 21 is accompanied with a decrease of the apparent inductance of device 22. The anodes 95 and 96 of the devices 21 and 22 are connected together and to the anode 58 of the oscillator device 20. The cathodes 97 and 98 of the devices 21 and 22 are connected respectively to ground through suitable biasing resistances 99 and 100, each being bypassed with a suitable condenser 101 and 102. By such connection, the cathodes 97 and 98 are maintained at the potential of the previously mentioned intermediate tap of inductance 55 of the tuned circuit 55, 56 for currents of carrier frequency. The reactance devices 21 and 22 are therefore effectively in shunt to the major part of the inductance 55, which portion is connected between the anode 58 and the positive terminal of the source 59.

In order to produce a flow of leading reactive current through the discharge device 21, the control electrode 93 is excited with voltage of carrier frequency from across the condenser 56. To provide this exciting voltage, a phase shifting network including a condenser 110 and a resistance 111 is connected in shunt to the capacity 56. The condenser 110 is connected between the control electrode 93 and anode 58, and the resistance

111 is connected between the control electrode 93 and, through an insulating condenser 112, the remaining terminal of condenser 56. Consequently, voltage of carrier frequency across the condenser 56 produces a leading current through the condenser 110 and resistance 111, so that a leading voltage appears across the resistance 111, and upon the control electrode 93. With a leading voltage on its control electrode 93, the reactance device 21 draws a leading current through its discharge path, and appears electrically as a capacity connected in shunt to a part of the inductance 55.

In similar fashion the reactance device 22 is connected to simulate an inductance. A phase shifting network including a resistance 113 and a condenser 114 is connected in shunt to the condenser 56. The condenser 114 is connected between the control electrode 94 of reactance device 22 and one terminal of the condenser 56, and the resistance 113 is connected between control electrode 94 and, through a suitable insulating condenser 115, to the anode 58.

The arrangement of the reactance devices 21 and 22 is especially desirable, since the currents drawn by these devices are nearly in exact quadrature with the voltage across the tuned circuit 55, 56. Since the voltage applied between the control electrode and cathode in the case of each of the reactance devices 21 and 22 is developed between the above-mentioned intermediate tap of the inductance 55, which is grounded for carrier current, and the intermediate tap of the associated phase shifting network, the voltage developed between these two points, by suitable adjustment of the condenser or resistance in each phase shifting network is effective to make that voltage assume a 90° phase relation with respect to voltage across the tuned circuit 55, 56. It is highly desirable that the reactance devices 21 and 22 draw such purely reactive current since they are thus much more effective to modulate the frequency of the oscillating device 20, especially at low frequencies where carrier current apparatus operates. At such low frequencies it is often difficult to modulate carrier frequency an amount sufficiently large with respect to signal frequencies to obtain satisfactory noise suppression. The arrangement described for the devices 21 and 22 is effective to provide a large shift in the operating frequency of the device 20.

Signals from the hand set 14 are conveyed to the carrier current transmitter and receiver unit along conductors 120, which may be a telephone line if the hand set 14 is at a long distance from the carrier current apparatus. The conductors 120 extend from the hand set 14 to a transformer 121 through which a pair of electron discharge devices 122 and 123 are excited. These discharge devices are arranged in balanced, or push-pull, relation, and their amplified output appears across a pair of serially connected resistances 124 and 125 in balanced relation. To apply the amplified signal across the resistance 124 to the control electrode 93 of reactance device 21, a network is provided including a pair of serially connected resistances 126 and 127, connected between ground and a point between resistance 111 and condenser 112. A point between the resistances 126 and 127 is coupled through a suitable coupling condenser 128 to a terminal of the resistance 124 on which amplified signal voltage is present. A suitable condenser 129 is connected in shunt to the resistance 127, and, with the re-

sistance 126, serves as a filter to prevent the appearance of voltage of carrier wave frequency across the resistance 127. Signal voltage across the resistance 124 is transmitted through condenser 128 to the control electrode 93 since condensers 110, 112 and 129 all have substantially large reactances at the frequencies of the amplified signal voltage.

A similar network is provided to impress amplified signal voltage across the resistance 125 on the control electrode 94 of the reactance device 22. A pair of serially connected resistances 130 and 131 are connected between ground and a point between the condenser 115 and resistance 113. A point between these resistances 130 and 131 is coupled through a suitable condenser 132 to a terminal of the resistance 125 on which amplified signal voltage appears. A suitable bypassing condenser 133 is connected in shunt to the resistance 131, and, with the resistance 130, forms a low pass filter so that voltage of carrier wave frequency does not appear across the resistance 131. Since the condensers 115, 114 and 133 have high reactance at signal frequencies, such frequencies are impressed through resistances 130 and 113 on the control electrode 94 in opposite phase to signal voltages on the control electrode 93.

It is highly desirable that means be provided to modulate the frequency of the generated carrier wave by an amount which is about equal to the highest signal frequency to provide substantial suppression of various types of undesired voltage which are introduced into the signal generated in the transmitter and transmitter to the receiver. It has been recognized that frequency modulation is highly desirable for the radio transmission of messages, but it has not been recognized that signal transmission on a power line by carrier current is susceptible of great improvement by the use of frequency modulation, and especially by the use of frequency modulation where the frequency shift is not much, if any, greater than the highest signal frequency. A large part of the interfering, or noise, voltage in a radio receiver, especially when the receiver is tuned to a weak signal, is due to energy whose periodicity lies within the band of frequencies to which the receiver is tuned. Noise voltage present on a power line presents no great difficulty under normal conditions because carrier energy levels on power lines are usually high enough that noise voltage present causes little interference. However, the carrier current is subject to certain influences, such as corona, which change its intensity in undesirable fashion. Furthermore, there are cases where the attenuation of a line is high and the received signal is low so that noise voltages may cause considerable interference. We have also determined that the transmission of signals by the frequency modulation of such carrier currents over power lines is effective to reduce the interference in such cases. It is desirable, in order that these influences be reduced to a minimum, that modulation of the frequency of the carrier current transmitted over the power line be produced in which the shift of frequency is about the same as, or not much greater than, the highest frequency component of the signals to be transmitted. The reactance devices 21 and 22, with the associated circuit thus described, are therefore highly useful in the transmission of signals over power lines by means of carrier current, because that arrangement is especially effective in modulating

the frequency of the carrier wave generated by the oscillator device 20 over a sufficient range of frequencies at the low frequencies used over power lines.

It is highly desirable for another reason that such signals be transmitted over a power line by modulating the frequency of the carrier wave over a band which is about the same as the highest frequency component of the signal. The transmitter so far described, as well as the receiver to be described hereinafter, have associated therewith control arrangements whereby the receiver is blocked and the transmitter started in response to signals from the hand set 14, and whereby the transmitter is blocked and the receiver started in response to carrier current on the power line 10. In order that these control circuits shall operate at extremely high speed, so that conversation between two stations along the power line 10 may most nearly approximate the normal telephone conversation, the effect of the large surges introduced in the transmitter and receiver by such rapid switching action must be minimized. The use of frequency modulation of the carrier wave for the transmission of such signals is highly desirable in order that these switching surges may be effectively eliminated.

In order to receive signals at relatively low signal-to-noise ratio, it is of great importance that the frequency modulation of the carrier wave shall not greatly exceed the highest frequency component of the audio signal. It is especially desirable to achieve, not the maximum amount of noise suppression, but a readily distinguished signal even though undesirably influenced in its transmission along the power line.

It is preferred that frequency modulation of the carrier wave shall not be less than the highest frequency component of the signal to be transmitted, since a smaller amount of frequency modulation actually reduces the highest frequency component of the signal which can be transmitted. It is at present believed, furthermore, that the maximum absolute carrier wave intensity at the receiver is achieved when the amount of frequency modulation is about the same as, or not much greater than, the highest frequency component of the signal to be transmitted.

The receiver associated with the transmitter including the oscillating device 20, as explained previously, includes a frequency converter device 24, an intermediate frequency amplifier 25, a limiting amplifier 26, a frequency discriminator circuit including diode detectors 27 and 28, and an audio amplifier including a pair of discharge devices 29 and 30. The frequency converter device 24 and its associated circuits, as well as the amplifier device 25 and its associated circuit, are similar to analogous apparatus in the receiver described in the above-mentioned copending application of Edwin W. Kenefake, Serial No. 450,449, filed July 11, 1942. The output tuned circuit 140 of the amplifier device 25 is coupled to the input tuned circuit 141 of the amplitude limiter device 26, in usual fashion. The control electrode 142 of the device 26 is connected to one terminal of the tuned input circuit 141, the other terminal of the input circuit 141 being connected to ground through a suitable grid resistance 143, shunted by a condenser 144. The condenser 144 has relatively small reactance at the frequency of waves for which the circuits 140 and 141 are tuned, and the resistance 143 is of sufficiently large value that the output of the amplitude limiter device 26 is substantially constant so long

as the input to the device 26 from the tuned circuit 140 is above a certain small minimum value.

The output of the amplitude limiter device 26, being of substantially constant amplitude, is demodulated in a suitable frequency discriminator circuit, such as that described and illustrated in Patent 2,121,103, Seeley, issued June 21, 1938. Detected signals, which correspond to the frequency modulation of the carrier current from the amplitude limiter device 26, appear across the serially connected resistances 150 and 151 of the discriminator circuit. These resistances are respectively connected in shunt to condensers 152 and 153 whose reactances are low at the frequency of the frequency modulated carrier current. It should be particularly noted that the resistances 150 and 151 are nowhere connected to ground, as in the above-mentioned Seeley patent, but that they are arranged so that signal voltage appears thereacross in balanced, or push-pull, relation with respect to ground.

The circuit arrangement by which the signal voltage across the resistances 150 and 151 is made to appear in balanced, or push-pull, relation, includes a pair of serially connected resistances 154 and 155 connected in shunt to the resistances 150 and 151, and having a point between such resistances 154 and 155 connected to ground. The point between the resistances 150 and 151 is bypassed to ground for carrier frequency current through a bypassing condenser 156. By such a circuit arrangement the detected signal voltages across the resistances 150 and 151 exist across the resistances 154 and 155 in balanced relation.

The power amplifiers 29 and 30 have their cathodes connected together, and through a resistance 160 to a suitable tap on a source 161 of potential, the tap being at a positive potential with respect to ground. The source 161 is provided to supply operating current to the receiver including the frequency converter device 24, the amplifier device 25, the limiter device 26, and the power amplifiers 29 and 30 and control device 45. The anodes 162 and 163 of devices 29 and 30 are connected to opposite terminals of the primary of the transformer 164, the center tap of the primary of transformer 164 being connected to the positive terminal of the source 161, whereby discharge current is supplied to amplifiers 29 and 30. The secondary of transformer 164 is connected across the conductors 120 so as to supply amplified signals to the hand set 14 from the receiver.

Detected signals across the resistances 154 and 155 are supplied across two serially connected voltage dividing resistances 165 and 166 through coupling condensers 167 and 168. The control electrodes 169 and 170 of the devices 29 and 30 are connected to respective adjustable taps on the voltage dividing resistances 165 and 166. A point between the voltage dividing resistances 165 and 166 is connected through a resistance 171, connected in shunt to a condenser 172, to the same intermediate tap of the source 161 to which the cathodes of the devices 29 and 30 are connected through the resistance 160. When current is not flowing through the resistance 171, the discharge current of the amplifiers 29 and 30 flowing through the resistance 160 provides a suitable operating bias potential for the control electrodes 169 and 170 of the amplifiers 29 and 30, so that the balanced signal potentials across the resistances 154 and 155 are amplified through the amplifiers 29 and 30 and supplied through transformer 164 to hand set 14.

The control device 45 is so arranged as to produce a flow of current through resistance 171 whenever there is no carrier wave in the tuned circuit 141, or whenever the intensity of the carrier wave in that tuned circuit is below a desired minimum intensity. To this end the anode 180 of the control device 45 is connected to a point between the resistances 165, 166 and 171, and the cathode 181 is grounded. The control electrode 182 is connected through a resistance 183 to a point between tuned circuit 141 and resistance 143, and this control electrode 182 is also connected to ground through a condenser 184.

In operation, this control device 45 acts to cut off the discharge current in the amplifiers 29 and 30 at all times except when a satisfactory detected signal exists across the resistances 154 and 155. Unless a carrier wave of sufficient intensity exists in the tuned circuit 141, the limited device 26 does not operate. That is, its control electrode 182 is not driven to sufficiently positive potentials to cause self-biasing action for the device 26 across the resistance 143 shunted by the condenser 144.

When carrier waves of sufficient intensity exist in the tuned circuit 141, such self-biasing action takes place, by rectification of the carrier wave on the control electrode 182 of the device 26, with corresponding production of a negative bias potential across the resistance 143. The negative bias potential across the resistance 143, developed when a carrier wave of sufficient intensity exists in the tuned circuit 141, is sufficient, when applied to the control electrode 182 of the control device 45, to reduce the discharge current in that device to zero. As explained above, when the device 45 is not transmitting any discharge current, so that no current is flowing through the resistance 171, the power amplifiers 29 and 30 are operative. When there is no carrier wave in the tuned circuit 141, or a carrier wave of less than a certain intensity, little or no negative bias voltage appears across the resistance 143, and the control device 45 passes a substantial discharge current, which flows through the resistance 171, and places a large negative bias potential on the control electrodes 169 and 170 with respect to the cathodes of the power amplifiers 29 and 30, so as to cut off the flow of discharge current in those amplifiers.

The control arrangement shown in Fig. 1a is identical in structure, although somewhat different in adjustment, with the control apparatus shown in Fig. 1a of the above-mentioned copending application, S. N. 450,449 of Edwin W. Kene-fake, filed July 11, 1942. Briefly, when sound impinges on the hand set 14, such sound signals are transmitted through the conductors 120 and through conductors 190 in Fig. 1a to the transformer 191. These sound signals from transformer 191 are amplified through discharge device 192 and impressed on the control electrode 193 of the vapor discharge device 40. The sound signals appearing on the control electrode 193 are sufficient to overcome a normally maintained negative bias potential on that control electrode and cause the vapor discharge device 40 to become conductive. Since the anode 194 of the vapor discharge device 40 is connected through the movable switch member 195 of relay 43 to conductor 50, which conductor in the absence of signals from the hand set 14 is maintained at a high positive potential by connection to the operating coil 196 of relay 43 and resistance 197 to the positive terminal of the source 198 of po-

tential, the conductor 50 is effectively grounded through the vapor discharge device 40, and the relay 43 is simultaneously energized. Connection of the conductor 50 to ground, as explained previously, is effective to start operation of the transmitter within a very short time interval determined by the size of resistance 53 and condenser 52, and since sound signals are impressed on transformer 121 from hand set 14, the carrier wave generated by the oscillation device 20 is modulated in frequency in accordance with such sound signals and transmitted over the power line 10 to distant stations.

Energization of the relay 43 subsequently causes its operation, and causes the direct grounding of conductor 50 through the movable switch contact 195, the vapor discharge device 40 thereafter having only the duty of maintaining relay 43 energized as long as signals appear from the hand set 14. Closure of the movable switch contact 198 of the relay 43 is effective to reduce the normally maintained negative bias potential on the control electrode 193 of vapor discharge device 40, whereby it is made easier for signals from the hand set 14 to maintain the device 40 conductive. Closure of the movable switch contact 199 of the relay 43 is effective to close a circuit for the relay which prevents its opening after deenergization for a predetermined time adjustable by adjustment of a variable resistance 200, all as explained in the above described application. Furthermore, closure of the movable switch contact 201 of relay 43 is effective to apply alternating potential from a suitable source 202 through the anode 194 of the vapor discharge device 40, whereby the anode potential of the device 40 is periodically reduced to a low value such that it can become non-conductive when signals from the hand set 14 cease.

When the conductor 50 is grounded through the vapor discharge device 40 or directly, through the movable switch contacts 195 of the relay 43, the double triode discharge device 44 is effective, as explained in the above described application, to produce a negative potential across the resistance 203, with which a condenser 204 is connected in shunt. Also, as explained in that above mentioned application, the oscillator and first mixer control electrode 205 of the device 24 are connected through a resistance 206 to the negative potential terminal of the resistance 203, the other terminal of resistance 203 being grounded.

In operation, the frequency converter device 24 is blocked by the negative potential applied from the resistance 203 to its control electrode 205 when signals appear from the hand set 14 in the shortest possible time. That is, the operation of the amplifier 192, the vapor discharge device 40, and the discharge device 44 in producing a negative bias potential across the resistance 203, and the application of that negative bias potential to the control electrode 205, is caused to take place in a relatively short time. For this purpose, the discharge device 44 should have low internal resistance when it is conductive, and the negative potential source from which the potential across resistance 203 is derived through the discharge path of the device 44 must have a low resistance.

After the receiver is blocked by the negative potential applied to the control electrode 205 in response to the appearance of signals in the hand set 14, the transmitter is turned on. The condenser 52 and resistance 53 are so proportioned

as to cause the desirable amount of time delay in turning on the transmitter. It is desirable that blocking of the receiver takes place as quickly as possible so that the time of turning on the transmitter may be minimized, resulting in minimum loss of the initial one or two cycles of the signals from the hand set 14. Such rapid blocking of the receiver is not effective to produce a surge which is amplified through the power amplifiers 29 and 30, because the discriminator circuit including the diodes 27 and 28 is balanced and cooperates with the limiter device 26, so that the receiver does not reproduce such a surge, even if the amplifier devices 29 and 30 were made operative by action of the control device 45. Such fast starting of the transmitter does produce a surge in the carrier wave transmitted by it, but the receiver is connected to the power line 10 which receives this carrier wave and the surge produced in it by rapid starting of the transmitter are arranged as the receiver shown in detail in Fig. 1b, and include limiter devices and balanced frequency discriminators, and are therefore not effective to reproduce a signal from such surges. These receivers are, however, effective to reproduce frequency modulation of the carrier wave, which is initiated immediately when the carrier wave is transmitted, since signals which start the transmitter from the hand set 14 immediately begin modulation of the frequency of the carrier wave.

When signals from the hand set 14 no longer appear, vapor discharge device 40 becomes non-conductive, and after a considerable time greater than that which usually elapses between parts of a single message, the relay 43 opens. The time delay after deenergization of the relay 43 before it opens may be of the order of 150 milliseconds. After the relay 43 opens, the carrier wave is no longer generated by the transmitter, the oscillator device 20 being deenergized, and that section of the device 44 which maintains the negative bias potential across resistance 203 also becomes non-conductive. Thereafter condenser 204 discharges slowly through the resistance 203, and eventually returns the control electrode 205 of the frequency converter device 24 to ground potential. The discharge time of the condenser 204 through resistance 203 may actually be fairly rapid, it being necessary only to assure that the frequency converter device 24 remain blocked until the oscillator device 20 has stopped oscillating. The discharge period for condenser 204 may be in the order of a few milliseconds.

When signals are not appearing from the hand set 14, so that the transmitter is turned off and the frequency converter device 24 operative, signals may appear from the power line 10 and be received by the receiver so as to block the transmitter and reproduce such signals in the hand set 14. When such signals are received and appear in the tuned circuit 141, they are impressed through a coupling condenser 210 upon the rectifier device 42, wherein they are detected to produce a continuous potential across the resistance 211 shunted by the condenser 212. So long as carrier current is received by the receiver, the continuous potential remains across the resistance 211 and is amplified through the double triode discharge device 41 to impress a negative bias potential on the second control electrode 213 of the vapor discharge device 40. All this action is similar to that described in the above mentioned application, S. N. 450,499, and is made to take place in the minimum possible time. As ex-

plained previously, when such signals appear in the tuned circuit 141, the control device 45 operates to make the power amplifiers 29 and 30 reproduce detected signals across the resistances 154 and 155 in the hand set 14.

The time after the appearance of a negative bias potential across the resistance 143 until the control device 45 becomes non-conductive is very short, being determined by the condenser 184 and resistance 183. It is necessary thereafter for the condenser 172 to discharge through the resistance 171, and only after such discharge are the amplifier devices 29 and 30 made operative. The time for such discharge is sufficient to insure that the vapor discharge device 40 is blocked, to prevent operation of the transmitter, before the amplifier devices 29 and 30 are made operative. The time after signals from the power line 10 are received by the receiver until the control device 45 operates to make the power amplifiers 29 and 30 operative should be a minimum. The arrangement of the amplifiers 29 and 30 in a balanced circuit insures that the action of the control device 45 in making them operative or inoperative has no effect of itself on the hand set 14. Such high speed operation is possible because there is no necessity for maintaining the amplifier devices 29 and 30 non-conductive until surges received from the power line 10 die out, since such surges are not detected by the receiver because of the use of frequency modulation with the limiter device 26 and the frequency discriminator circuit including the diodes 27 and 28. Since such frequency modulation arrangements are utilized, it is possible to make the receiver operative long before received surges die out, and the use of the balanced power amplifier stage makes it possible to put the receiver into operation at such high speed, because that balanced stage does not reproduce switching surges caused in the receiver for reproduction by the hand set 14.

After signals from the power line 10 cease, the bias potential across resistance 143 disappears, and the control device 45 becomes conductive immediately to block operation of the amplifier devices 29 and 30. Immediately thereafter, in a time determined by the time constants of the resistance 211 and condenser 212, the negative bias potential on the control electrode 213 of vapor discharge device 40 is allowed to disappear, leaving the transmitter in condition such that it may be started if signals appear from the hand set 14.

It is only by the integrated use of such an ultra high speed control system together with frequency modulation circuits which effectively do not respond to switching surges that our carrier wave transmitter and receiver are able to operate so rapidly and with so little loss of the beginning of a signal that conversations may be carried on between stations including such apparatus with as much facility as over a normal telephone line. As explained previously, the transmission of the signals by modulation of the frequency of the carrier waves is of great additional advantage in reducing the peculiar type of interference with the transmission of a carrier wave experienced along a high voltage power line. By the use of this frequency modulation in which the carrier wave frequency is shifted over a band of frequencies whose width is about the same as the highest signal frequency, a very great reduction in the carrier wave power necessary to produce an intelligible signal at the receiver is achieved.

Where this small shift in frequency is employed amounting to about the same as the highest signal frequency, and where modulation of the frequency is made strictly proportional to intensity of the signal, less than $\frac{1}{2}$ as much power is necessary to transmit a signal than if the signal were transmitted by amplitude modulation of the carrier wave. This reduction in power may be made even more favorable if pre-emphasis is utilized. That is, if higher signal frequencies are made to shift the frequency of the carrier wave a greater amount than lower signal frequencies, it has been found that about fifty times as much power is required to transmit a signal of the same intelligibility by amplitude modulation of the carrier.

While we have shown and described a particular embodiment of our invention, it will be obvious to those skilled in the art that changes and modifications may be made without departing from our invention in its broader aspects, and we therefore aim in the appended claims to cover all such changes and modifications as fall within the true spirit and scope of our invention.

What we claim as new and desire to secure by Letters Patent of the United States is:

1. In a system for transmitting signals over an electric line subject to disturbing influences of the nature of that due to corona, the combination of a carrier wave source, a signal source, means for modulating the frequency of a carrier wave from said carrier wave source in accordance with the intensity of signals from said signal source and for impressing such frequency modulated carrier waves on said line, and receiving means for receiving said frequency modulated carrier wave from said line and reproducing said signal from the modulations of frequency of said carrier wave, said carrier wave being subject to undesired signal frequency modulation of intensity of the nature of that due to corona during its

passage along said line, said receiving means including means for preventing the reproduction along with said signals of such modulations of intensity of said carrier wave.

- 5 2. In combination, an electric line subject to disturbing influences of the nature of that due to corona, a carrier wave source, a signal source, means for modulating the frequency of a carrier wave from said carrier wave source in accordance with the intensity of signals from said signal source and for transmitting said modulated carrier wave over said line, means for receiving said modulated carrier wave from said line and for reproducing signals in accordance with the frequency modulation of said carrier wave, said carrier wave being subject to undesired signal frequency amplitude modulation in its passage along said line of the nature of that due to corona, said receiving means including amplitude limiting means for said carrier wave and a balanced frequency discriminator for detecting frequency modulation of said carrier wave and the modulation of the frequency of said carrier wave being of the same order as the highest frequency component of said signal whereby minimum carrier wave power is required to transmit said signal with satisfactory intelligibility from said signal source to said receiving means.
- 10 3. In a carrier current system for an electric line having the characteristic of introducing noise by causing signal frequency amplitude modulation of the carrier of the nature of that due to corona, means for impressing on the line a carrier modulated in frequency by a signal, and means for receiving said carrier from said line and for reproducing said signal from the modulations in frequency of the carrier, said receiving means including means for rejecting amplitude modulation of the carrier.
